UNITED STATES PATENT OFFICE.

JOHN EWART, OF ARLINGTON, MASSACHUSETTS, ASSIGNOR OF ONE-FOURTH TO JOSEPH A. EWART, OF SALEM, MASSACHUSETTS, AND ONE-HALF TO SHERBURNE & COMPANY, OF BOSTON, MASSACHUSETTS, A FIRM.

DOOR-CHECK.

950,566.

Specification of Letters Patent.

Patented Mar. 1, 1910.

Application filed November 8, 1909. Serial No. 526,747.

To all whom it may concern:

Be it known that I, JOHN EWART, of Arlington, in the county of Middlesex and State of Massachusetts, have invented cer-
tain new and useful Improvements in Door-
Checks, of which the following is a specification.

This invention relates to devices for yield-
ingly securing car and other doors in an
open position, and has especial reference to
the type of door check shown in Letters Patent
of the United States, No. 594,613, dated
November 30, 1897. Said patented door
check comprises a member adapted to be at-
tached to a floor, and to yield vertically rela-
tively thereto, said member having an in-
clined portion, and a recess above the incline,
and an arm member adapted to be attached
to a door and to engage the recess of the
floor member when the door is fully opened,
the floor member being pressed upwardly by
a spring and adapted to yield downwardly
to permit the disengagement of the arm
member from it by the application of clos-
ing force to the door.

Heretofore, the arm member has been rig-
idly attached to the door with no provision
for adjustment. It has been found in prac-
tice that owing to various causes the arm
and floor members become relatively dis-
placed from their coöperative positions, so
that in some cases the arm member fails to
properly coincide with the floor member.

The present invention has for its object to
enable the arm member to be adjusted to dif-
ferent positions relatively to the door, so
that in case of failure of the arm member to
properly coincide with the floor member, the
difficulty can be corrected by an adjustment
of the arm member.

The invention consists in the improve-
ments which I will now proceed to describe
and claim.

Of the accompanying drawings, forming
a part of this specification, Figures 1 and 2
represent perspective views, respectively, of
an arm member and an adjusting member
embodying my invention. Fig. 3 represents
a sectional view of a portion of a door to
which the arm member and adjusting mem-
ber shown in Figs. 1 and 2, are applied.
Fig. 4 represents a view similar to Fig. 3,
showing a different adjustment of the arm
member.

The same reference characters indicate the 55
same parts in all the figures.

In the drawings,—12 represents the arm
member of a door check of the character
shown in the above mentioned Patent No.
594,613, said arm member having a flat base 60
13 provided with holes 14 adapted to engage
and closely fit attaching screws 15 which se-
cure the arm member to a door 16. The
floor or socket member which coöperates
with the arm member and is engaged with 65
the floor of a car or other structure at a suit-
able point to engage the arm member when
the door is opened, is or may be of the con-
struction represented in the above mentioned
patent to which reference may be had for a 70
complete illustration and description of the
floor member.

Instead of applying the arm member so
that its base 13 bears directly upon the door,
I separate the base from the door sufficiently 75
to permit the interposition between the base
and the door of an adjusting member 17.
This member is preferably a cast metal plate
of malleable iron or any other suitable
metal, and is provided with a flat inner side 80
adapted to bear on the door, and with two
oppositely inclined faces 18, 19 on its outer
side, said faces forming bearings for the end
portions of the base 13. The adjusting 85
member is also provided with longitudinal
slots 20 arranged to receive the attaching
screws 15, the said slots being so arranged
that the adjusting member 17 is adapted to
be adjusted longitudinally so that it may
occupy either the position shown in Fig. 3, 90
or that shown in Fig. 4, or any desired in-
termediate position. When the adjusting
member is in the position shown in Fig. 3,
the lower end of the base bears on the face
18 at a point above the lower end of the lat-
ter, the upper end of the base bearing on
the extreme upper portion of the face 19.
The base is therefore inclined so that the
outer end of the arm has the minimum pro-
jection from the door, its outer end having 100
the minimum height above the floor. When
the adjusting member is in the position
shown in Fig. 4, the lower end of the base
bears on the extreme lower portion of the
face 18, and its upper end bears on the face 105
19 at a point below the upper end of the lat-
ter, the base being therefore so inclined that
the arm has the maximum projection from

the side of the door, and its outer end has the maximum elevation above the floor.

It is evident that various intermediate positions of the arm member may be secured by intermediate adjustments of the adjusting member. The attaching screws should of course be loosened prior to the adjustment of the member 17, and then tightened to hold said member and the arm member at the desired adjustment. The adjusting member is preferably provided with longitudinal edge flanges 22 adapted to bear on the longitudinal edges of the base 13.

I claim:

- 15 1. In a door check of the character stated, an arm member carried by a door and adapted to engage a complementary member adjacent to the door, said arm member having a base, combined with an adjusting member interposed between the base and door, and adapted to occupy different positions relatively to the base and door, and to support the arm member in different positions relatively to the door.
- 20 2. In a door check of the character stated,

an arm member carried by a door and adapted to engage a complementary member adjacent to the door, said arm member having a base having screw-engaging holes, combined with an adjusting member adapted to be interposed between the base and door and provided with oppositely inclined faces forming bearings for the end portions of the base, and with longitudinal slots to receive attaching screws engaged with said holes, said slots permitting a longitudinal adjustment of the adjusting member relatively to the base plate and door.

3. As an article of manufacture, an adjusting member adapted to receive the base of a door check arm, and having oppositely inclined faces and longitudinal screw-receiving slots.

In testimony whereof I have affixed my signature, in presence of two witnesses.

JOHN EWART.
